Primary Examiner — Keli L Hill*(74) Attorney, Agent, or Firm* — Sheridan Ross PC(57) **CLAIM**

The ornamental design for a speaker, as shown and described.

DESCRIPTION

FIG. 1 is a front perspective view of the speaker showing the new design;

FIG. 2 is a right perspective view of a speaker thereof, the left perspective view being a mirror image of the right perspective view;

FIG. 3 is a top plan view thereof;

FIG. 4 is a front elevation view thereof; and,

FIG. 5 is a right elevation view thereof, the left elevation view being a mirror image of the right elevation view.

The broken lines shown are included for the purpose of illustrating portions of the speaker that form no part of the claim.
